Exs.-1

Exs.-2

FIG. 1 is a bottom perspective view of a combined bag and information containing pocket showing my new design;

FIG. 2 is a bottom perspective view showing the side opposite that seen in FIG. 1, the end not shown being the same in appearance as the end shown;

FIG. 3 is a view similar to FIG. 1 but showing a modified form of my new design; and

FIG. 4 is a view similar to FIG. 2 showing the modified form.

The dash lines in the drawings indicate score lines.

The characteristic features of my design reside in the appearance and configuration of the bottom of the bag.

This application is a continuation of applications Ser. Nos. D. 220,551 and D. 220,553, both filed Jan. 24, 1972.

I claim:

The ornamental design for a combined bag and information containing pocket, as shown and described.
